UNITED STATES PATENT OFFICE

136,134

DESIGN FOR A TELEPHONE BOOTH OR THE LIKE

Willis L. Manning, Park Ridge, Ill., assignor to
Burgess Battery Company, Freeport, Ill., a cor-
poration of Delaware

Application February 20, 1943, Serial No. 109,595

Term of patent 14 years

To all whom it may concern:

Be it known that I, Willis L. Manning, a citizen of the United States, residing at Park Ridge, in the county of Cook and State of Illinois, have invented a new, original, and ornamental Design for a Telephone Booth or the like, of which the following is a specification, reference being had to the accompanying drawings, forming part thereof.

Fig. 1 is a perspective view of a telephone booth or the like showing my new design;

Fig. 2 is a top plan view thereof;
Fig. 3 is a front elevational view thereof;
Fig. 4 is a side elevational view thereof;
Fig. 5 is a bottom plan view thereof.
I claim:
The ornamental design for a telephone booth or the like, as shown.

WILLIS L. MANNING.
